UNITED STATES PATENT OFFICE.

DMITRI DUBASSOFF, OF PHILADELPHIA, PENNSYLVANIA.

DESIGN FOR A BRACELET.

Application filed March 10, 1927. Serial No. 21,081. Term of patent 3½ years.

To all whom it may concern:

Be it known that I, DMITRI DUBASSOFF, a citizen of Russia, residing at Philadelphia, in the county of Philadelphia and State of Pennsylvania, have invented a new, original, and ornamental Design for Bracelets, of which the following is a specification, reference being had to the accompanying drawings, forming part thereof.

In the drawings herewith, Fig. I is a plan view of a bracelet, showing my new design; and

Fig. II is a front edge view of the same.

I claim:

The ornamental design for a bracelet, as shown.

DMITRI DUBASSOFF.
